POWER CAN OPENER

Henry Sachs, 866 S. Wooster, Los Angeles, Calif.

Filed Apr. 21, 1958, Ser. No. 729,970

4 Claims. (Cl. 30—4)

This invention relates to an improved power actuated can opener.

It is an object of this invention to provide a motor driven can opener which will sever the lid of a beaded can of any configuration or size.

It is a further object of this invention to provide such an opener wherein maximum contact between cutter and the can is obtained, permitting severing adjacent the side wall of the can and avoiding jagged edges.

It is a further object of this invention to provide means for maintaining the can in proper alignment during cutting.

Other objects and advantages will be readily apparent from the following description:

In the drawings:

Figure 1 is a side elevation in section of the opener.

Figure 2 is a view taken along line 2—2 of Figure 1.

Figure 3 is a fragmentary front elevation of the opener.

Figure 4 is a fragmentary view illustrating the cutting action.

Figure 5 is a view taken along line 5—5 of Figure 3.

Figure 6 is a view taken along line 6—6 of Figure 3.

Figure 7 is a view taken along line 7—7 of Figure 3.

Figure 8 is a view taken along line 8—8 of Figure 3.

Figure 9 is a view similar to Figure 3 with the opener pivoted to the can inserting position.

Figure 10 is a view taken along line 10—10 of Figure 3.

Figure 11 is a view taken along line 11—11 of Figure 1.

Figure 12 is a view taken along line 12—12 of Figure 3.

A base 20 is mounted upon four legs 22 and has bolted thereto two upright plates 24 and 26. A housing 28 encloses base 22 and plates 24 and 26. The housing is preferably of suitable plastic or the like and encloses the mechanism except for the actual cutting device, generally designated at 30, which will hereinafter be described in detail.

A suitable electric motor 32 is housed between plate 24 and housing 28 which, by means of a conventional plug and cord, is connected to a source of electric power. A switch 34 cutting motor 32 on or off is mounted upon plate 24 and is spring biased to an open position and closed by pivoting of arm 36 (see Figure 11) mounted upon shaft 38, upon which operating lever 40 is mounted. Shaft 38 is rotatably supported in plates 24 and 26 and pivoting of lever 40 rotates same and hence arm 36.

The driven shaft 42 of motor 32 passes through a suitable opening in plate 24 and drives shaft 44 through a suitable gear train at the desired speed. All of the gears and their respective shafts are rotatably mounted between plates 24 and 26 with the first gear on the driven shaft 42 and last gear on shaft 44. Shaft 44 passes through plate 26 and has mounted on its extremity, drive wheel 48 having the conventional ratchet teeth on its periphery.

Pivots mounted outside housing 28 is a plate 50 by

2

means of pin 52 (see Figure 5). The pin has a non-circular extremity 54 which projects through a similarly shaped hole in plate 24. Pin 52 has fixed two washers 56 and 58 thereon, one on either side of plate 26. Washer 56 forms a seat for spring 60 which bears against plate 26, urging the pin to withdraw inside housing 28 while washer 58 limits withdrawal.

A left threaded screw 61 clamps plate 50 to pin 52 so that the plate 50 may move away from plate 36.

Plate 50 has a hole 62 therein through which shaft 44 projects mounting wheel 48 in front of plate 50. On the opposite side of hole 62, plate 50 has a slot 64 formed therein. A screw 66 having an enlarged head projects through slot 64 and fastens into lever 40. Lever 40 has a circular portion 68 which encircles the extremity of shaft 38 and is rigidly secured thereto. A curved segment 70 of the lever projects outwardly and joins the handle portion 72.

As lever 40 is pivoted, screw 66 rotates about the axes of shaft and moves in slot 64. When the handle 72 is substantially vertical, plate 50 is pivoted upwardly, as seen in Figure 9 and the cutter 74, mounted on the plate 50, is moved away from wheel 48, permitting a can to be inserted between same.

When the handle is pivoted to its other extreme approaching horizontal, the cutter 74 is at its lowermost position adjacent wheel 48. The switch 34 is adjusted to close at the terminal point of pivoting when screw 66 reached the extremity of slot 64, actuating wheel 48 only when in this position. The shape of slot 64 is an open V with the length thereof determining the arc of pivoting of handle 72 and the apex 76 and angle of the slot on either side thereof determining the speed of pivoting of plate 50. By varying the angularity, the mechanical advantage can be controlled. It is desirable to provide maximum mechanical advantage when the cutter pierces the can, that is, during the last 30° of arc of travel of the handle.

After a can of the type usually utilized for packaging foods and the like is inserted between wheel 48 and cutter 74 and the latter has pierced the top of the can. The can is positioned by a pair of springs 75 and 77. The motion of the cutter as same approaches the wheel is substantially vertical, permitting the positioning springs to be positioned extremely close to same. Horizontal spring 75 bears downwardly against the bead of the can while vertical spring 77 bears against the side wall of the can, urging same into the cutter. This spring arrangement permits cutting of all types of beaded cans, irrespective of whether same are round or not and adapts the device to many sizes of cans.

The horizontal spring passes through a suitable hole 78 in plate 50 and is coiled around holder 80 and abuts stop 82. Vertical spring 77 fits in housing 84 formed on plate 50 and is retained by pin 86.

The cutter 74 is secured to plate 50 by a screw 88 which screws into a protuberance 90. The cutter 74 is inclined at approximately twenty degrees to wheel 48, plus or minus two degrees, and has its cutting edge beveled approximately forty degrees; thus in cooperation with spring 77, the cutter will cut at precisely the junction of the top and side wall of the can, leaving no jagged edges.

A magnet 92 may be pivotally mounted upon plate 50 as illustrated in Figure 8, for example, to hold the top of the can when severed.

The serrated driving wheel 48 is driven counterclockwise, as viewed in Figure 9; that is, vertical spring 77 is in advance of the cutter, urging the can into the cutter while horizontal spring is positioned at the discharge of the cutter and prevents the can from climbing out of alignment.

While what hereinbefore has been described is the preferred embodiment of this invention, it is readily apparent that alterations and modifications can be resorted to without departing from the scope of this invention and such alterations and modifications are intended to be included within the scope of the appended claims.

I claim:

1. A can opening device comprising, a frame, a power driven wheel supported on said frame, a plate pivotally mounted upon said frame, a cutter wheel carried upon said plate, a slot in said plate, a movable element supported by said frame projecting within said slot and movable to bring said cutter wheel into cutting relationship with said power wheel, a vertical spring and a horizontal spring mounted upon said plate immediately adjacent said cutter wheel for engaging the can being cut.

2. A can opening device comprising, a frame, a power driven wheel supported on said frame, a plate pivotally mounted upon said frame, a cutter wheel carried upon said plate, a slot in said plate, a movable element supported by said frame projecting within said slot and movable to bring said cutter wheel into cutting relationship with said power wheel, a vertical spring and a horizontal spring mounted upon said plate immediately adjacent said cutter wheel for engaging the can being cut, said power wheel being driven in a direction whereby said vertical spring is in advance of said horizontal spring adjacent the discharge of said cutter wheel.

3. A can opening device comprising, a frame, a power driven wheel supported on said frame, a plate pivotally mounted upon said frame, a cutter wheel carried upon said plate, a slot in said plate, a movable element supported by said frame projecting within said slot and movable to bring said cutter wheel into cutting relationship

5

with said power wheel, a vertical spring and a horizontal spring mounted upon said plate immediately adjacent said cutter wheel for engaging the can being cut, said power wheel being driven in a direction whereby said vertical spring is in advance of said horizontal spring adjacent the discharge of said cutter wheel, said cutter wheel being inclined at substantially a twenty degree angle to said power wheel.

10

4. A can opening device comprising, a frame, a power driven wheel supported on said frame, a plate pivotally mounted upon said frame, a cutter wheel carried upon said plate, a slot in said plate, a movable element supported by said frame projecting within said slot and movable to bring said cutter wheel into cutting relationship

15

with said power wheel, a vertical spring and a horizontal spring mounted upon said plate immediately adjacent said cutter wheel for engaging the can being cut, said power wheel being driven in a direction whereby said vertical spring is in advance of said horizontal spring adjacent the discharge of said cutter wheel, said cutter wheel being inclined at substantially a twenty degree angle to

20

said power wheel, a vertical spring and a horizontal spring mounted upon said plate immediately adjacent said cutter wheel for engaging the can being cut, said power wheel being driven in a direction whereby said vertical spring is in advance of said horizontal spring adjacent the discharge of said cutter wheel, said cutter wheel being inclined at substantially a twenty degree angle to said power wheel, and having a substantially forty degree bevel on its cutting edge.
